UNITED STATES PATENT OFFICE.

EDWARD THOMAS JONES, OF NEW ORLEANS, LOUISIANA.

SWITCH.

Application filed December 27, 1921. Serial No. 525,153.

To all whom it may concern.

Be it known that I, EDWARD THOMAS JONES, a citizen of the United States, residing at New Orleans, in the parish of Orleans and 5 State of Louisiana, have invented a certain new and useful Improvement in a Switch, of which the following is a specification.

My invention relates broadly to electric switches and more particularly to an electric 10 switch construction for operation with radio telegraph and telephone transmitting and receiving apparatus.

Reference is made to my Patent 1,415,179, dated May 9, 1922, for radio controlling devices in which I have claimed broadly the 15 device of the present application.

The object of the present invention is to provide an electrical switch construction operative for rapidly transferring connections 20 of a radio antenna system between the receiving and transmitting apparatus.

Another object of my invention is to provide an antenna transfer switch construction which simultaneously cuts in the power 25 for the transmitter and closes auxiliary circuits when the switch is thrown to transmitting position to connect the antenna with the transmitting apparatus.

A further object of the invention is to 30 provide an antenna switch construction having simplified parts readily assembled and capable of quantity production in manufacture.

Another object of the invention is to provide an arrangement of switch blades such 35 that the receiving apparatus is protected from heavy surges and discharges from the antenna system when the switch is thrown from transmitting to receiving, and also to provide a means for protecting the receiver 40 at all times from heavy electrical discharges which might surge in the antenna system.

Other and further objects of my invention will be understood from the following specification with reference to the accompanying 45 drawings, in which:

Figure 1 is a plan view of the antenna transfer switch; Fig. 2 is a side elevation of the antenna transfer switch illustrating 50 the receiving side of the switch; Fig. 3 is a front end view of the switch showing the operating knob; Fig. 4 is a side elevation of the switch looking at the transmitting side; and Fig. 5 is a perspective view of the 55 switch showing the electrical connections

with radio transmitting and receiving apparatus.

The switch construction comprises broadly a horizontal insulated base or other supporting member and a vertical insulated support 60 carried thereby at the top of which a horizontal shaft is supported in an elongated bearing. The shaft is rotatable by means of an insulated hand knob. The shaft carries at its opposite ends a set of switch blades 65 disposed at acute angles with relation to the vertical support. The blades are adapted to cooperate with switch contact jaws carried in different positions on the insulated vertical support. The switch blades and cooperating contact jaws serve to connect the receiving apparatus with the antenna system when the shaft is rotated in one direction and serve to connect the transmitting apparatus with the antenna system and at the 70 same time connect the power with the transmitter and close auxiliary power circuits when the shaft is rotated in the opposite direction. The blades are arranged such that in transferring the antenna from the transmitter to the receiver the transmitter power is cut off before the antenna system is disconnected from the transmitting apparatus and before the receiving apparatus is connected with the antenna system whereby opportunity is given for the antenna to drain 75 any accumulated charge before being thrown into connection with the receiving apparatus. While in receiving position the transmitter switch blade and contact jaw may be 80 so related as to form a protective spark gap circuit through the transmitter inductance across the receiver to prevent heavy surges from passing through the primary of the 85 receiver circuit.

Referring to the drawings, the insulated base or supporting member of the switch is indicated by reference character 1 and the insulated vertical support for the switch at 2. The bearing member 3 is carried upon the upper extremity of the vertical support and provides an elongated bearing for rotatable shaft 46 operative by insulated knob 20 secured to the end of the shaft by means of socket 44 and set screw 45. The rotatable shaft 46 is secured at the opposite end of bearing 3 by nut 47. Switch blades 5 and 6 and insulated section 11 are rotated by said shaft. The blades and insulated section 11 are angularly dis- 105 110

posed upon the shaft at acute angles with relation to the vertical support. The blade 5 is referred to as the transmitter switch blade and is shorter in length than the 5 receiver switch blade 6 which is secured adjacent thereto. Blade 5 cooperates to enter switch contact jaws 7 secured to the insulated vertical support 2 by binding post 9 below the bearing number 3. The opposite 10 switch blade 6 is adapted to cooperate and make connection with switch contact jaws 8 secured upon the lower portion of the vertical support by binding post 10. Electrical connection with an antenna system 15 is had with bearing member 3 by means of binding post 4 secured to the bearing member 3 by machine screw 4^a. An insulated section 11 is carried by the rotatable switch shaft adjacent operating knob 20 and socket 20 44 by angular member 50 to which the insulated section 11 is secured by machine screws 49. The insulated section 11 carries at its extremity a terminal 12 adapted to enter and close an electrical circuit between 25 jaws 14 and 15 carried on the lower portion of the vertically insulated support on the transmitting side of the switch. The contact jaws 14 and 15 are secured to the insulated vertical support 2 of the switch by 30 screws 16^a and 17^a, one of each of which are secured to binding posts 16 and 17 on the opposite sides of the vertical support.

Referring to Fig. 5 of the drawings the switch is illustrated with the rotatable shaft 35 in such position that the transmitting switch blade 5 is just leaving the contact jaws 7 and a switch blade 6 is just ready to enter the contact jaws 8 to connect the antenna to the receiver and in this position the insulated section 11 with its terminal 12 is entirely free from the contact jaws 14 and 15. The antenna 5 of the radio system connects to binding post 4. The receiving apparatus is connected to binding post 10 and includes in circuit the primary winding 34 and ground connection 33. Inductively associated with the primary winding is secondary winding 35 tuned by variable condenser 36. Any form of receiver may be connected to this adjustable circuit 35 and 36. The receiver illustrated 40 comprises a thermionic vacuum tube having a heated filament 39 energized by battery 38, grid element 40 and plate element 41. Grid condenser and grid leak 37 are connected in circuit with grid 40. The plate 41 connects to the output circuit including B battery 43 and telephone receivers 42.

The transmitting apparatus connects to 45 binding post 9 on the switch and the circuit includes inductance 21 and ground 22. Inductively coupled to the inductance 21 is primary winding 23 of the closed circuit of the transmitter which in this case is represented as a rotary spark gap oscillating cir- 50 cuit 23, 24 and 25. The circuit is charged from the secondary winding 26 of transformer 27. The primary circuit 28 of the transformer 27 is energized from source of power 30 and the circuit opened and closed 70 through key 32. The rotary spark gap 24 is driven by motor 29 also operated from the source of power 30. The power circuit through generator 30 for the transformer 27 and the motor 29 is only completed when 75 the switch knob 20 is rotated to move terminal 12 into contact jaws 14 and 15 which electrically connect through binding posts 16 and 17 with the power circuits. The operating knob 20 may be secured at the opposite end of the shaft 46, if desired. Greater personal protection is offered the operator however, by placing the operating knob at the end of the shaft opposite the blades 5 and 6 to reduce the accidental touching of these blades by the operator while 80 changing the switch from one position to another.

In the operation of the antenna transfer switch the operator grasps switch knob 20 85 and rotates the shaft in a counter-clockwise direction in changing from a receiving period to a transmitting period. Switch blade 6 leaves the contact jaws 8 disconnecting the receiver from the antenna system 90 and the switch blade 5 moves into contact jaws 7 connecting the antenna system with the transmitting apparatus. Terminal 12 then moves between contact jaws 14 and 15 completing the power circuits for the transmitter. Upon completion of the transmitting period the operator rotates the switch knob in a clockwise direction to transfer the antenna from the transmitting apparatus to the receiving apparatus. The power circuit 105 is first disconnected from the transmitter by the displacement of terminal 12 from contact jaws 14 and 15. The power is then thrown off of the transformer circuit and the rotary spark gap is brought to rest. Switch blade 5 moves out of contact jaws 7 permitting a draining of the antenna of any charges 110 retained from the transmitting period for a differential of time after the power has been cut off and before the receiver is connected 115 with the antenna. Switchblade 6 then moves into contact jaws 8 connecting the antenna to the receiver. The receiver may be protected from heavy surges by moving the blades in such position as to allow a small 120 clearance between the transmitter blade 5 and contact jaws 7 whereby a protective spark gap to ground through the low impedance path of the transmitting inductance 21 is provided across the receiver.

It will be understood that the base or supporting member 1 may be of any suitable material and that it is not necessary that it be made of insulating material. Furthermore, I may dispense with the base 125 130

and mount the elongated support 2 directly upon a vertical panel or other supporting member.

While I have described the invention with relation to radio systems the switch has numerous applications and I intend no limitations upon its use other than as set forth in the appended claims.

What I claim and desire to secure by Letters Patent of the United States is as follows:

1. A switch comprising a supporting member, an insulated vertical elongated support thereon, a rotatable shaft longitudinally positioned on the extremity of said support, a bearing member for said shaft substantially throughout the length of said support, laterally projecting switch blades carried by said shaft, contacts arranged on opposite sides of said elongated support and adapted to receive said switch blades in their respective rotated positions.

2. A switch comprising a supporting member, an insulated vertical elongated support carried thereby, a plurality of contacts carried on opposite sides of said support, a shaft carried longitudinally upon the upper extremity of said support, a journal for said shaft substantially throughout the length of said support, switch blades carried by said shaft disposed at acute angles with said support and adapted to be received by said contacts upon rotation of said shaft in either direction.

3. A switch comprising a supporting member, a vertical elongated support carried thereby, a plurality of contacts secured to opposite sides of said support, a rotatable shaft mounted longitudinally along the top of said support, a bearing member for said shaft extending substantially throughout the length of said support, switch blades carried by said shaft, one of said blades having a metallic terminal at the extremity thereof electrically insulated from said shaft, said terminal being adapted to engage one of said contacts, and an insulated knob for rotating said shaft whereby said blades are connected to respective contacts on opposite sides of said support.

4. A switch comprising a supporting member, an insulated vertical elongated support carried thereby, a shaft carried longitudinally at the upper extremity of said support, an insulated knob at one end of said shaft and an acutely angled switch blade carried at the opposite end of said shaft and a second blade carried by said shaft adjacent said knob, means supporting said shaft throughout the distance between

said blades, contacts secured to opposite sides of said support and adapted to receive said acutely angled blade when said shaft is rotated in either of its extreme positions and a contact on one side of said support adapted to receive said second blade, said second blade having a metallic terminal separated from said shaft by an insulated section and adapted to close an electrical circuit through said contact.

5. A switch comprising in combination a supporting member, a vertical elongated support carried thereby, a rotatable shaft carried at the extreme upper portion of said support and journaled substantially throughout its length, switch blades carried by said shaft and arranged at an acute angle with said support, a single contact secured to one side of said vertical support, a plurality of contacts carried on the opposite side of said support and means whereby said switch blades are connected with said contacts upon rotation of said shaft.

6. A switch comprising in combination a supporting member, a vertical elongated support carried thereby, a rotatable shaft carried at the extreme upper portion of said support, a bearing member for said shaft substantially throughout the length of said support, switch blades carried by said shaft and arranged at an acute angle with said support, a contact secured to one side of said vertical support, another contact secured to the opposite side of said support, a bifurcated contact carried on said opposite side of said support and means whereby said switch blades are connected with said contacts upon rotation of said shaft.

7. A switch comprising in combination a supporting member, a vertical elongated support carried thereby, a rotatable shaft carried at the extreme upper portion of said support, an insulated knob at one end of said shaft, an acutely angled switch blade carried by said shaft at the end opposite said knob, a second blade carried by said shaft at the end adjacent said knob, means supporting said shaft substantially throughout the distance between said blades, a contact secured to one side of said vertical support, another contact secured to the opposite side of said vertical support, each of said contacts cooperating with said acutely angled switch blade and a bifurcated contact carried by said opposite side of said support and arranged to cooperate with said second blade, said second blade including an insulated section and a metallic terminal.

EDWARD THOMAS JONES.
